[57] CLAIM

The ornamental design for a surgical vessel loop, as shown and described.

DESCRIPTION

FIG. 1 is a perspective view of a surgical vessel loop, showing my new design with all other sides being identical to that showing;

FIG. 2 is a left side elevational view thereof, the right side elevational view being a mirror image thereof;

FIG. 3 is a fragmentary top plan view thereof, the bottom plan view being a mirror image thereof; and

FIG. 4 is a fragmentary front elevational view thereof, the rear elevational view being a mirror image thereof.

FIG. 1

FIG. 3

FIG. 2

FIG. 4
